UNITED STATES PATENT OFFICE

136,888

DESIGN FOR A NURSING BOTTLE

Howard H. Ganson, Buffalo, N. Y., assignor to
Hygeia Nursing Bottle Company, Inc., Buffalo,
N. Y., a corporation of New York

Application May 18, 1942, Serial No. 106,943

Term of patent 14 years

To all whom it may concern:

Be it known that I, Howard H. Ganson, a citizen of the United States, residing at Buffalo, in the county of Erie and State of New York, have invented a new and original Design for Nursing Bottles, of which the following is a specification, reference being had to the accompanying drawing, forming a part thereof.

Figure 1 is a side elevational view of the nurs-

ing bottle embodying my design. Figure 2 is a top plan view of the same with the nipple portion omitted for convenience of illustration.

The dominant features of my design reside in the portions shown in full lines.

I claim:

The ornamental design for a nursing bottle, substantially as shown and described.

HOWARD H. GANSON.
